PROCESS FOR DESULPHURIZING ALKYL PHENOLS

Walter J. Hund and Samuel Benson Thomas,
Oakland, and Daniel B. Luten, Jr., Berkeley,
Calif., assignors to Shell Development Company,
San Francisco, Calif., a corporation of Delaware

No Drawing. Application November 22, 1937,
Serial No. 175,876

11 Claims. (Cl. 260—624)

This is a continuation-in-part of our copending application Serial No. 144,658, filed May 25, 1937, and relates to an improvement in the method of purifying alkyl phenols containing aromatic mercaptans i. e., thiophenols and other organic non-mercaptan sulphur compounds. More particularly it deals with an improved method for desulphurizing alkyl phenols recovered from petroleum oils by highly efficient extraction means.

10 In the above mentioned co-pending application Serial No. 144,658, we have shown that in order to recover the largest portion of alkyl phenols from petroleum oils, methods of extraction must be employed which yield extracts containing besides the alkyl phenols high percentages of impurities, notably neutral oils, carboxylic acids, and sulphur and nitrogen compounds. Some of these impurities are removed from the alkyl phenols with extreme difficulty 15 only, and the expenses due to consumption of chemicals and losses of alkyl phenols are often excessive.

20 We have further shown that by a process in which a series of individually known steps is carried out and combined in a certain manner, good yields of "commercially pure" alkyl phenols, i. e., which are sufficiently pure to meet commercial requirements, are obtained at a much lower cost than has been possible heretofore. This process 25 consists essentially of the following steps:

(1) Extracting a petroleum oil containing alkyl phenols, while in the liquid state, with an aqueous alkali metal hydroxide solution of an original concentration of 35-50% under conditions to form two layers and separating the layers;

(2) subjecting the aqueous layer to a prolonged steaming with substantially saturated steam to drive off certain impurities and to precipitate a sludge which is separated, and continuing to steam until no further sludge precipitates;

(3) carbonating the steamed clear liquid aqueous layer with carbon dioxide to liberate alkyl phenols, thereby forming two layers, and separating the layers;

(4) rapidly distilling the liberated alkyl phenols under vacuum;

(5) if desired, further purifying the distilled alkyl phenols by oxidation, preferably with air at a temperature between about 140°-150° C. followed by redistillation, and the redistilled product may further be blown at about room temperature to remove possible foul odors.

55 The distillates resulting from Step 4 contain as

their main impurities sulphur compounds, largely in the form of aromatic mercaptans, i. e., thiophenols, and the object of the subsequent oxidation step is mainly to eliminate these thiophenols.

It is a purpose of the present invention to improve the above process, particularly the oxidation step, so that commercially pure alkyl phenols of even lower contents of thiophenols and other sulphur compounds can be had, if possible, at no increased cost. In some instances where an exceptionally low sulphur content is required, consumption of treating chemicals may, however, have to be raised.

One of the difficulties of our former procedure consisted of the necessity of having to carry out the oxidation with air at relatively high temperatures, because at lower temperatures the rate of oxidation of thiophenols to disulphides is too slow in most cases. With increasing temperatures the rate increases; however, at the same time undesirable side reactions set in, some of which consume alkyl phenols and lead to the formation of dehydrogenated products of unknown composition.

Furthermore it is sometimes difficult, if not impossible, to remove by distillation at least a portion of the disulphides from alkyl phenol mixtures, particularly if the latter has a long boiling range, because relatively low boiling thiophenols may form disulphides boiling within a boiling range of the higher boiling alkyl phenols. Moreover at the relatively high temperatures of distillation, even when distilling under high vacuum, aromatic disulphides may be reconverted to thiophenols.

Now we have discovered that the oxidation of thiophenols in the alkaline state proceeds satisfactorily at about room temperature. At this temperature undesirable reactions do not take place to a material extent. With increasing temperature the rate of oxidation of thiophenols to disulphides increases, but at the same time a reversal of this reaction, namely reduction of disulphides to thiophenols at the expense of alkyl phenols also accelerates. Therefore, temperatures substantially above room temperature not only fail to give better conversions of thiophenols to disulphides, but may result in material losses of alkyl phenols.

We have found that at temperatures above about 80° to 90° C. the reversed reaction proceeds at such a rapid rate that for practical purposes no oxidation of thiophenols to disulphides takes place, and alkyl phenols only are attacked. Similarly, if an alkali alkyl phenolate solution con-

taining disulphides is heated to about 90° C. or higher, thiophenols are reformed rapidly and alkyl phenols are oxidized even in the absence of air. For these reasons we maintain during 5 the oxidation and afterwards as long as disulphides are present temperatures below about 80° to 90° C. and preferably below about 50° C. At 10 50° C. or lower the reformation of thiophenols from disulphides is sufficiently slow so that oxidation of thiophenols to disulphides and separation of the latter from the alkali alkyl phenolate solution can be achieved without appreciable loss of alkyl phenols.

In addition to enabling satisfactory oxidation 15 with air without undue interference from side reactions, when operating in the alkaline state at about room temperature, this method has the further advantage of making possible easy separation of the disulphides from the alkali alkyl phenolate solution as will be described later.

Accordingly the present invention comprises the steps of effecting the oxidation of sulphur compounds and in particular thiophenols, contained in the alkyl phenols, with air at about 25 room temperature, while in solution of an alkaline-reacting liquid medium which itself is not substantially oxidized under the conditions of the treatment, thereby forming disulphides, and separating the latter from the alkaline solution 30 without substantially raising the temperature. The oxidation for the removal of thiophenols may be effected after completed steaming and separation of precipitated sludge, immediately preceding the carbonating step, described in the said co- 35 pending application. By so doing no chemicals in excess of those used in our older process are required, and yet after carbonation and vacuum distillation of the liberated alkyl phenols a product is obtained which has a sulphur content considerably lower than that obtainable by air blowing 40 the free alkyl phenols in the acid state after completed vacuum distillation as was formerly done.

An alternative method which may have to be 45 resorted to, where sulphur requirements are exceedingly low, consists of redissolving the liberated vacuum distilled alkyl phenol in a suitable alkaline liquid medium to produce a phenolate solution, air blowing the latter at about room 50 temperature, separating disulphides, and reacidifying the blown solution to liberate the alkyl phenols.

If desired, both modifications may be combined, i. e., the alkyl phenolate extract after being 55 steamed and separated from precipitated sludge is air blown, disulphides are separated, and the blown solution is carbonated to liberate the alkyl phenols. The alkyl phenols are vacuum distilled, redissolved in a suitable alkaline medium and the 60 resulting solution is again blown with air. Disulphides are separated, the blown solution is acidified and liberated phenols may be redistilled.

The entire extraction and treating process is as follows:

65 A petroleum oil containing alkyl phenols, such as a cracked distillate boiling between about 175° to 300° C. is extracted with an aqueous solution of an alkali metal hydroxide.

The step of extracting the petroleum oil consists essentially of treating the liquid oil with an 70 amount of an aqueous alkali metal hydroxide solution, preferably sodium or potassium hydroxide, of an original concentration of 35-50%, which amount contains a quantity of free hydroxide 75 only slightly in excess of that required to convert

all of the alkyl phenols contained in the oil to alkali metal alkyl phenolates. It is known that when alkyl phenols are added to an aqueous caustic alkali solution of about 35-50% concentration a precipitation of phenolates takes place, and upon further addition of a certain minimum critical amount of alkyl phenols, which amount is less than that required to consume all of the free alkali metal hydroxide, the precipitated phenolates are redissolved in the aqueous phase. Thus by adding to an alkali metal hydroxide solution of the above strength the minimum critical amount of alkyl phenols required to form a single aqueous phase of phenolates, a solution is obtained which contains besides the phenolates considerable quantities of free alkali metal hydroxide. This critical amount varies considerably with the concentration of the hydroxide and the type of alkyl phenols added. For instance, when using a mixture of alkyl phenols of an average molecular weight of xylenols, the critical amount required to produce a single phase would be as follows for aqueous sodium hydroxide solutions of various concentrations:

Original concentration of NaOH in caustic solution	Critical amount of alkyl phenols percent by weight of solution
Per cent	
35	37
40	42
45	45
50	47

The resulting phenolate solution containing free alkali metal hydroxide is the most effective extractant for alkyl phenols from hydrocarbon oils, if contacted with the oil in the proper proportion. The amount of alkaline alkyl phenolate solution used to treat a given amount of oil containing alkyl phenols should be such that the amount of alkyl phenols in the oil is sufficient to convert a portion only of the free alkali hydroxide to alkyl phenolates, and the enriched phenolate solution thus produced should preferably contain a mol ratio of alkyl phenols to alkali metal between the limits of .80 and .98.

In its most efficient form the extraction is carried out as follows: An alkaline alkyl phenolate solution containing at least the critical amount of alkyl phenols is continuously circulated. At some point of the circuit it is contacted with an amount of oil containing alkyl phenols, so that a substantial portion of the free alkali metal hydroxide is converted to phenolates. The oil and the aqueous phenolate solutions are then separated, the oil being substantially free from alkyl phenols after this extraction. A portion of the phenolate solution is then withdrawn from circulation to be treated as will be described hereinafter. The remainder of the alkyl phenolate solution is mixed with an amount of fresh caustic alkali solution of 35-50% concentration sufficient to replace the amount of alkali metal withdrawn before, and the resulting mixture containing free alkali is again contacted with fresh oil as described above.

While by this method of extraction substantially complete removal of alkyl phenols from petroleum oil is accomplished, the alkyl phenols so extracted are highly contaminated with impurities. Besides alkyl phenols, other substances are dissolved in the aqueous phenolate solution, notably naphthenic and other carboxylic acids,

neutral hydrocarbons, sulphur compounds, nitrogen bases, resinous bodies, etc., and in addition the aqueous solution may contain varying amounts of emulsified heavy tarry material, part 5 of which may settle out upon prolonged standing. Alkyl phenols liberated from the untreated phenolate solution by acidification may contain 10 or more per cent of neutral oil, sulphur in excess of 1%, and nitrogen bases as high as 6 10 or 8%.

The phenolate solution containing neutral, basic and sulphurous impurities is now subjected to a prolonged steaming preferably at substantially normal pressures and with substantially 15 saturated steam. The use of highly superheated steam or the heating of the phenolate solution substantially above 100° C. is disadvantageous because it leads to excessive losses of alkyl phenols by vaporization and by way of undesirable 20 condensation and/or decomposition reactions of the phenols themselves.

This steaming in combination with the described method of extracting the alkyl phenols from the petroleum oil is an essential part of our 25 process. Unless it is carried far enough it is almost impossible to obtain by any subsequent treatment, or combination of simple treatments, except by double use of alkali metal hydroxide extraction and acidification as for instance described by Merrill in U. S. Patent 2,000,244, alkyl phenols of sufficient stability and purity to meet 30 even the most liberal commercial requirements.

During the early stages of the steaming period, neutral oils, nitrogen bases, sulphur compounds 35 and a small portion, amounting to less than 20%, of the alkyl phenols of relatively low acidities are vaporized and removed overhead. Steaming, however, must be continued for some time after the removal of the volatilizable compounds has 40 been substantially completed. This latter point is recognized when the exhaust steam, upon condensation, no longer turns turbid. While steaming proceeds, sludge is being formed and precipitated, and when the phenolate solution is allowed to rest, two separate layers form, an aqueous layer and a heavier sludge layer. Upon continued steaming the amount of sludge formed 45 eventually reaches a maximum, so that when the sludge is separated and the desludged aqueous layer is further steamed, no additional sludge is formed. The time of steaming required to 50 reach this point of maximum sludge formation normally varies between about 4 and 16 hours, alkyl phenolates derived from relatively low-boiling distillates normally requiring shorter time for complete steaming than alkyl phenolates obtained from heavier oils.

It is absolutely essential that steaming be carried out to the maximum point of sludge formation. While the reactions responsible for the formation of sludge are not quite understood, it appears that its production is due to a combination 60 of removing neutral oils which act as dispersers for actual sludge, i. e., sludge which is present from the beginning, and condensation reactions which take place during the steaming after removal of neutral oils and lead to the formation of additional sludge, for convenience called herein potential sludge. Apparently nitrogen bases 65 take active part in these condensation reactions forming high boiling compounds, and although a considerable portion of the nitrogenous condensation products may remain in the alkaline solution after steaming, they later form part of the 70 tarry residue produced in the subsequent vacu-

um distillation of the liberated alkyl phenols. It appears that considerable time is required to condense the nitrogen bases, and if steaming is too short, condensation remains incomplete and the unreacted portion thereof will go overhead in 5 the subsequent vacuum distillation jointly with the alkyl phenols. Since nitrogen bases, together with sulphur compounds are the most harmful and obnoxious impurities in commercial alkyl phenols, it is readily seen how important 10 it is to conduct the steaming to the point of maximum sludge formation.

We are aware that alkyl phenols have been produced by extracting coal tars with aqueous caustic alkali solution, blowing the extract with 15 steam, liberating the phenols and distilling and blowing same with air. However, in contrast to the above, phenolate solutions obtained from coal tar distillates with alkali metal hydroxide solutions of customary concentrations, which are 20 generally much lower than those hereinbefore described, do not produce sludge upon steaming, perhaps because phenolate solutions obtained with relatively weak alkali hydroxide solutions are comparatively little contaminated with 25 impurities, and also because coal tar phenols, having been in contact with ammonia at elevated temperatures in the course of their formation have already undergone a preliminary purification. But, whereas extraction of phenols from 30 coal tar distillates with relatively weak alkali hydroxide solutions is commercially practical because the concentration of phenols in these distillates may be of the order of 7 to 35%, (see U. S. Patent 1,991,979), the concentration of alkyl 35 phenols in petroleum oils is usually below .5% and more often about .1% or below. Obviously more effective means of extraction must be applied to petroleum oils than to coal tar distillates, and the greater efficiency of extraction is 40 at least partly responsible for the greater difficulties experienced in the subsequent refining of the alkyl phenols, impurities which are normally associated with petroleum being extracted as well. 45

Aside from the relative amounts of the respective impurities, it also appears that there are considerable differences regarding their nature. As pointed out before, in petroleum alkyl phenols a class of little known nitrogen bases constitutes the 50 most harmful impurities, which nitrogen compounds seem to be almost completely absent from coal tar phenols. For this reason the extent of the steaming just sufficient to remove neutral oils has proven adequate in the purification of 55 coal tar phenols, but in the case of purification of petroleum phenols has met with failure; and before our discovery that steaming must be prolonged to give time for the condensation reactions described above it was impossible to obtain 60 commercially pure alkyl phenols in the simple manner proposed by us.

When the steaming has progressed so that upon further steaming no additional sludge is formed, the precipitated sludge is separated from 65 the phenolate solution. Usually the desludged solution contains emulsified organic matter other than sludge, which refuses to separate at this point. In such a case diluting the phenolate solution with at least an equal volume of water 70 will readily break the emulsion. We have found it very convenient as a rule to dilute the solution to about 10%. If this does not produce a complete break of the emulsion, resort may be had to centrifugation or filtration through a suitable 75

medium which is preferentially wetted by the organic matter.

The phenolate solution is now perfectly clear and of much lighter color than before steaming, since neutral oils capable of dissolving sludge have been removed substantially quantitatively as well as most sludge-forming compounds and a portion of the sulphur compounds. This clear phenolate solution may now be blown with air at temperatures between about 0° and 90° C. and preferably below 50° C., for instance at about normal room temperatures. At temperatures below 0° C. the rate of conversion of thiophenols to disulphides is too low to be practical, and at temperatures above about 90° C. the reversion of disulphides to thiophenols proceeds at such a rate as to prevent accumulation of disulphides, and results in losses of alkyl phenols, as has been described hereinbefore.

The time required for blowing in the absence of catalysts may be of the order of 10 to 60 hours depending upon the exact temperature of blowing, the sulphur content of the alkyl phenols, the desired degree of desulphurization, etc. Oxidation catalysts may be added to accelerate the rate of formation of disulphides. Suitable catalysts are, for instance the metals, oxides and sulphides of copper, lead, manganese and ferrous metals, or mixtures thereof, in particular the nickel and lead sulphides. However, other known oxidation catalysts may also be used.

The disulphides formed in the oxidation are largely insoluble in the phenolate solution. They are compounds of high wetting powers for silicates, metals and many other solids and consequently tend to adhere to them. They may be separated from the phenolate solution by conventional method such as settling, centrifuging, filtering through a filter bed of solids; or washing with a hydrocarbon solvent such as naphtha, benzene, or other suitable organic liquid which is immiscible with the phenolate solution and which does not extract phenols from phenolate solutions to an appreciable extent, or by a combination of these methods. Frequently the disulphides appear as a finely dispersed suspension, in which case settling and centrifuging are insufficient and extremely vigorous agitation with a solvent or filtration through a bed of sand or the like may be necessary.

The separation of the disulphides is preferably carried out without substantially raising the temperature, because upon heating even in the acid state, but more so in the alkaline state, the aromatic disulphides tend to revert to their respective mercaptans. In this respect aromatic disulphides differ considerably from aliphatic disulphides which normally can be distilled without material decomposition. Therefore phenolate solutions containing separated and/or dissolved aromatic disulphides should not be heated above about 90° C., and a temperature below about 50° C. is preferably maintained before and during the removal of the latter.

The desulphurized phenolate solution is now carbonated by introducing into it carbon dioxide or a gas containing carbon dioxide such as flue gas, or lime kiln gas, etc. in an amount so that preferably the resulting aqueous solution contains about an equi-molar mixture of carbonate and bicarbonate. Since phenols are acids weaker than carbon dioxide, they are liberated while the stronger carboxylic acids as well as hydrogen sulphide, if present, remain in the aqueous solution as alkali metal salts. Together with the

alkyl phenols, organic hydrosulphides such as thio phenols and mercaptans not removed by steaming, are liberated. The liberated alkyl phenols form a separate layer and are removed from the resulting aqueous carbonate solution in which the carboxylic acids are retained. The alkyl phenols may be water washed, such a wash often lowering the sulphur content by about .2 to 3%. If desired, the carboxylic acids may be liberated and recovered from the carbonated solution, for instance by treating same with a relatively strong acid, such as sulphuric, sulphurous, hydrochloric, phosphoric acid, etc.

The separated alkyl phenols which usually contain a relatively small amount of sulphur compounds and more or less of dark colored resinous or tarry matter, are now subjected to a quick distillation, preferably a flash distillation under a reduced pressure, e. g., below about 25 mm. mercury. Since the resinous or tarry compounds associated with the crude alkyl phenols are thermally unstable and crack very readily, thereby forming both neutral oils and tar, distillation must proceed at the lowest practical temperature, preferably below 180° C. and at the highest rate possible. The resulting distillates are mixtures of alkyl phenols of light colors, good color stabilities and very low sulphur contents.

As has been indicated hereinbefore instead of proceeding as described, the steps of blowing with air and separating disulphides may be carried out after completed vacuum distillation. In this case the alkyl phenols which may or may not have had an air blowing treatment are redissolved in an alkaline liquid medium to form a liquid solution. We prefer to use an aqueous alkali metal hydroxide in which to dissolve the phenols, although other suitable bases such as various amino bases for instance aqueous ammonia, alkyl amines, alkanol amines, alkylenediamines, aniline, aqueous quaternary ammonium bases may be used instead. The resulting phenolate solution is then blown for several hours with air at a temperature preferably below about 50° C. such as room temperature, and disulphides are then separated by one of the methods described before which may be applicable. The blown and desulphurized phenolate solution is carbonated to liberate the alkyl phenols and if desired the latter may be redistilled.

The reductions in the sulphur content which can be had by our improved process are well illustrated in the following examples:

A mixture of alkyl phenol which was produced in accordance with the method of our co-pending application Serial No. 144,658, had a mercaptan sulphur content of 1.5 prior to blowing with air at 140° to 150° C. After blowing for 10 hours at 145° C. and redistilling, under vacuum the mercaptan sulphur content was 0.5%.

When, however, producing alkyl phenols from the same source by the method of this invention, according to which the alkyl phenolate extract was blown following completed steaming and sludge separation, the mercaptan sulphur content was reduced to .05%. If instead of air blowing the aqueous phenolate extract, the vacuum distilled phenols containing 1.5% of mercaptan sulphur were redissolved in a 10% aqueous caustic soda and the resulting phenolate solution was blown at room temperature for 10 hours, the mercaptan sulphur content after separation of disulphides was of the order of .001 to .005%; and if air blowing in alkaline solution was employed twice, namely before and after vacuum

distillation contents of mercaptan sulphur were well below .001%.

We claim as our invention:

1. In the process of refining alkyl phenols containing aromatic mercaptans, the steps comprising blowing the alkyl phenols with air at a temperature between 0° and 90° C. while in solution of an alkaline-reacting liquid medium stable under the conditions of the treatment, for a time sufficient to convert mercaptides to disulphides which are largely insoluble in said solutions and form a separate phase, and removing the separated disulphides from the solution while maintaining a temperature below about 90° C.
2. In the process of refining alkyl phenols containing aromatic mercaptans, the steps comprising blowing the alkyl phenols with air at a temperature between 0° and 50° C. while in solution of an alkaline-reacting liquid medium stable under the conditions of the treatment, for a time sufficient to convert mercaptides to disulphides which are largely insoluble in said solutions and form a separate phase, and removing the separated disulphides from the solution while maintaining a temperature below about 50° C.
3. In the process of refining alkyl phenols containing aromatic mercaptans, the steps comprising oxidizing the alkyl phenols while in solution of a liquid aqueous alkali metal hydroxide, by blowing same with air at a temperature between 0° and 90° C., for a time sufficient to convert mercaptides to disulphides which are largely insoluble in said solutions and form a separate phase, and removing the separated disulphides from the solution while maintaining a temperature below about 90° C.
4. The process of claim 3 in which the oxidation is carried out in the presence of an oxidation catalyst capable of accelerating the oxidation of mercaptans to disulphides.
5. In the process of refining alkyl phenols containing aromatic mercaptans, the steps comprising blowing the alkyl phenols with air at a temperature between 0° and 90° C. while in solution of an alkaline-reacting liquid medium stable under the conditions of the treatment, for a time sufficient to convert mercaptides to disulphides which are largely insoluble in said solutions and form a separate phase, and filtering the solution while maintaining a temperature below about 90° C.
6. In the process of producing commercially pure alkyl phenols from a petroleum distillate containing same and aromatic mercaptans, comprising extracting the distillate with a quantity of an aqueous alkali metal hydroxide solution of 35 to 50% concentration to form an alkali metal alkyl phenolate solution containing aromatic mercaptides, free alkali metal hydroxide and a sufficient amount of alkyl phenols to prevent precipitation of the alkyl phenolates, steaming the resulting aqueous alkaline solution for a time sufficient to expel volatile impurities and to precipitate actual and potential sludges, separating the sludges from the solution of alkyl phenolates and mercaptides, carbonating the desludged solution with an amount of carbon dioxide sufficient to liberate alkyl phenols and mercaptans, thereby forming two layers, an alkyl phenol layer containing aromatic mercaptans and an aqueous layer, separating the layers, distilling the alkyl phenols and mercaptans under conditions to prevent substantial cracking, and subjecting the alkyl phenols to an oxidation treatment to convert mercaptans to disulphides, the improvement comprising effecting the oxidation by blowing the alkyl phenols containing mercaptans with air at a temperature between 0° and 90° C. while in solution of an alkaline-reacting liquid medium stable under the conditions of the treatment, for a time sufficient to convert mercaptans to disulphides which are largely insoluble in said solutions and form a separate phase, and removing the separated disulphides from the alkaline solution while maintaining a temperature below about 90° C.
7. In the process of producing commercially pure alkyl phenols from a petroleum distillate containing same and aromatic mercaptans, comprising extracting the distillate with a quantity of an aqueous alkali metal hydroxide solution of 35 to 50% concentration to form an alkali metal alkyl phenolate solution containing aromatic mercaptides, free alkali metal hydroxide and a sufficient amount of alkyl phenols to prevent precipitation of the alkyl phenolates, steaming the resulting aqueous alkaline solution for a time sufficient to expel volatile impurities and to precipitate actual and potential sludges, separating the sludges from the solution of alkyl phenolates and mercaptides, carbonating the desludged solution with an amount of carbon dioxide sufficient to liberate alkyl phenols and mercaptans, thereby forming two layers, an alkyl phenol layer containing aromatic mercaptans and an aqueous layer, separating the layers, distilling the alkyl phenols and mercaptans under conditions to prevent substantial cracking, and subjecting the distilled mixture to an oxidation treatment to convert mercaptans to disulphides, the improvement comprising redissolving the distilled mixture in a liquid alkali reacting medium stable under the conditions of the treatment, to produce an alkyl phenolate and mercaptide solution, blowing the solution with air at a temperature between 0° and 90° C., for a time sufficient to convert mercaptides to disulphides which are largely insoluble in said solutions and form a separate phase, and removing the separated disulphides from the alkaline solution while maintaining a temperature below about 90° C.
8. In the process of refining alkyl phenols containing aromatic mercaptans, the steps comprising blowing the alkyl phenols with air at a temperature between 0° and 90° C. while in solution of an alkaline-reacting liquid medium stable under the conditions of the treatment, for a time sufficient to convert mercaptides to disulphides which are largely insoluble in said solution and form a separate phase, and extracting the resulting mixture with an organic preferential solvent for disulphides which is immiscible with the solution to remove disulphides, while maintaining a temperature below about 90° C.
9. In the process of refining alkyl phenols containing aromatic mercaptans, the step comprising blowing the alkyl phenols with air at a temperature between 0° and 90° C. while in solution of an alkaline-reacting liquid medium stable under the conditions of the treatment, for a time sufficient to convert mercaptides to disulphides which are largely insoluble in said solution and form a separate phase, and extracting the resulting mixture with a hydrocarbon solvent to remove disulphides, while maintaining a temperature below about 90° C.
10. In the process of refining alkyl phenols containing aromatic mercaptans, the step comprising blowing the alkyl phenols with air at a temperature between 0° and 90° C. while in solution

of an alkaline-reacting liquid medium stable under the conditions of the treatment, for a time sufficient to convert mercaptides to disulphides which are largely insoluble in said solution and 5 form a separate phase, and filtering the solution through a filter medium which is preferentially wetted by the disulphides, while maintaining a temperature below about 90° C.

11. In the process of refining alkyl phenols 10 from a petroleum distillate containing same and aromatic mercaptans, the steps comprising extracting the distillate with a strong aqueous solution of an alkali metal hydroxide to produce an alkali metal phenolate solution containing

mercaptides and volatile impurities, steaming said phenolate solution to expel said volatile impurities, contacting the steamed solution with air at a temperature between 0° and 90° C. for a time sufficient to convert at least a portion of said mercaptides to disulphides which are largely insoluble in said phenolate solution and form a separate phase, and removing the separated disulphides from the phenolate solution while maintaining a temperature below about 90° C. 5
